[57] CLAIM

The ornamental design for wind instrument transporting pack, as shown and described.

DESCRIPTION

FIG. 1 is a perspective view of a wind instrument transporting pack showing my new design;
FIG. 2 is a top plan view thereof;
FIG. 3 is a left side elevational view thereof;
FIG. 4 is a front elevational view thereof;
FIG. 5 is a right side elevational view thereof;
FIG. 6 is a bottom plan view thereof;
FIG. 7 is a second embodiment of a wind transporting pack thereof;
FIG. 8 is a top plan view thereof;
FIG. 9 is a left side elevational view thereof;
FIG. 10 is a front elevational view thereof;
FIG. 11 is a right side elevational view thereof; and,
FIG. 12 is a bottom plan view thereof.
